DESIGN FOR A FINGER REST

Otto Robert White, New York, N. Y.

Application May 12, 1942, Serial No. 106,870

Term of patent 14 years

To all whom it may concern:

Be it known that I, Otto Robert White, a citizen of the United States of America and resident of the city of New York, county of Queens, and State of New York, have invented a new, original, and ornamental Design for a Finger Rest, of which the following is a specification, reference being had to the accompanying drawing, forming part thereof.

In the drawing:

I claim:

The ornamental design for a finger rest, substantially as shown.

OTTO ROBERT WHITE.
